UNITED STATES PATENT OFFICE.

GEORGE W. HAURY, OF CHICAGO, ILLINOIS.

INTERNAL-COMBUSTION ENGINE.

1,157,387.

Specification of Letters Patent.

Patented Oct. 19, 1915.

Application filed March 26, 1914. Serial No. 827,272.

To all whom it may concern:

Be it known that I, GEORGE W. HAURY, a citizen of the United States, residing at Chicago, in the county of Cook and State of Illinois, have invented certain new and useful Improvements in Internal-Combustion Engines, of which the following is a specification.

My invention relates to improvements in internal combustion engines, and more particularly to four-cycle gas engines employing mechanically-operated valves to control the admission of fuel charges to the cylinder, and expulsion of the spent charges.

One of the objects of my invention is to provide an engine of the slide-valve type, having improved and efficient valve mechanism.

More specifically an object of my invention is to locate the valve mechanism axially beyond the engine-cylinder so that the valve structure and its operating connections may be exteriorly located with respect to the engine frame, for ready accessibility, interchangeability and attention, and so that the movable valve parts are free from wearing engagement with the piston and its cylinder and from direct action of the ignited charges.

Another object of my invention is to simplify and improve the valve construction, minimizing the number of parts and combining them for efficiency and durability in operation.

A further specific object of my invention is to provide a construction in which the external valve mechanism employing, for each part controlled thereby, only a single slide-member, is made gas tight by simple and adequate construction; and a further object is to provide a construction applicable to already-built engines so that, in many instances, puppet valve engines may be changed to my slide-valve construction.

Other and further objects of my invention will become apparent to those skilled in the art from the following description taken in conjunction with the accompanying drawings in which—

Figure 1 is a central vertical section through a two cylinder engine; Fig. 2 is a side elevation of such engine; Fig. 3 is an enlarged perspective detail of the valve structure detached; Fig. 4 is a perspective detail of one valve section; Fig. 5 is a detail of an operating cam, taken on line 5—5 of Fig. 2; Fig. 6 is a horizontal section on line 6—6 of Fig. 1; Fig. 7 is a similar section on line 7—7 of Fig. 1; and Fig. 8 is a similar section on line 8—8 of Fig. 1.

60

In the specific construction shown in the drawing, 10 indicates in general a two cylinder four-cycle gas engine. The number of cylinders, of course, is unimportant as far as applicability of my invention is concerned. The cylinders 11, water jacketed as at 12, are mounted on the crank casing 13, that bears the crank shaft, 14, driven by the pistons 15 through the connecting rods 16, such construction typifying any suitable 65 structure; although in the practice of my invention it is preferable that the cylinders shall have no lateral openings thereto within the range of movement of the pistons.

65

17 indicates any suitable gearing driving 70 in one-to-two relation, a valve-actuating shaft 18, which is preferably mounted above the engine head; the valve shaft 18 being mounted in split bearings in the standards 19 carried by the engine frame, as one convenient form of construction. Thus the 75 valve shaft is readily removable.

75

Each cylinder has its valve mechanism, preferably constituting a detachable unit, mounted in a valve head which preferably 80 is disposed longitudinally beyond the confines of the cylinder proper 11. In the specific construction shown each valve head 85 comprises a base plate 21 secured to the engine cylinder and having centrally an annular axial extension 22, of smaller diameter than the engine-cylinder 11, constituting the inner cylinder of the valve mechanism and extending axially for a distance 90 suitable to give adequate bearing to the 95 valve member to be described. Above its lower end, and preferably below its upper end, said valve-cylinder 22 is closed by a transverse head wall 23 through which preferably extends a spark plug 24, so that said 100 cylinder is divided into the ignition chamber 25, which constitutes in effect a continuation of the combustion chamber in cylinder 11, and an outer recess 26 in which the spark plug is protectedly located. In 105 take and exhaust ports 27 and 28, each extending through a considerable arc, open transversely into the chamber 25, preferably in the same plane and diametrically opposite each other; these ports preferably being 110 located near the inner end of the extension 22. The exterior of the cylinder 22 is ma-

chined to coöperate with the valve and is provided with packing rings 29 and 29' respectively located above and below the ports 27, 28.

5 Surrounding the inner valve cylinder 22 is an external valve sleeve 30 having a base flange 31 bolted as at 32 through the base 21 to the engine frame. Intake and exhaust ports 33 and 33' open through the sleeve 30, 10 preferably in a plane nonalining with the plane of ports 27 and 28, and preferably at a material distance axially beyond said ports 27, 28. The ports 33 and 33' are narrow horizontal openings of considerable arcuate 15 extent and outwardly they open to chambers 34 and 35 which communicate respectively with the intake and exhaust manifolds 36 and 37. While the valve cylinder 22 and sleeve are preferably separable parts 20 detachable from the cylinder 11, these parts may all be cast in a single piece.

In the interspace between the cylinder 22 and sleeve 30, works the cylindrical slide valve structure generally indicated at 40. 25 The valve structure is preferably made in two independent complementary sections or members 41 and 42 jointly constituting a complete cylinder, diametrically divided so that, for simplicity of construction, the 30 fronting radial surfaces 41' and 42' of the two slide sections may make direct sliding contact with each other, and so that the arcs of the ports may be made of great angular measurement, and consequently narrow. 35

Each valve member 41 and 42 has within it a passage for effecting communication between the two ports or port-couple 27—33 or 28—33' in the cylinder and sleeve, with 40 which it coats. Such passage, 43, in each valve member, is a vertical chamber having a bottom opening, at 44, through the inner wall and a top opening, at 45, through its outer wall. This construction, it will be observed, leaves a long uninterrupted bearing surface above the inner opening 44, and a long uninterrupted bearing surface below the outer opening 45, so that gas leakage along the valve from port-to-port is substantially impossible on account of the elongated bearing surfaces. Further it is my preference that the valve structure should be somewhat shorter than the depth of the space between the valve-head walls, so as to 50 leave a clearance space 49 at the bottom to act as an oil-receiving chamber.

At its upper extremity, each valve section is provided with ear 50, connected by a suitable arm 51 extending from the eccentric strip 52 encircling the eccentric 53 on the valve shaft 18; this being one effective connection for silently operating the slide valve section.

It will be observed that the valve members are readily separable from the walls of

the head, so that inspection and repair may be made with minimum labor. It will further be observed that the construction enables the cylinder of the engine to be made without lateral opening in the combustion chamber proper, and that the construction herein described may be applied to puppet-valve engines already built, substituting the valve-head in lieu of the ordinary cylinder head, and so substituting slide valve action for the puppet valve action. 70

In operation, it will be understood that the eccentrics operate the valves in proper time to open the exhaust valve during the scavenging stroke of the engine, and, immediately upon commencement of the intake stroke to open the intake valve, each valve section when in open position affording a large and effective passage-way vertically through the walls of the valve member from the port in the cylinder wall of the head to the manifold port in the surrounding sleeve. 80

While each valve member provides but a single sliding part, the extended valve member, hollow for a material distance between 90 its interior and exterior openings, makes an effective seal against gas escape and receives adequate bearing for durability and certainty of operation. No part of the valve proper is within the combustion chamber, 95 subject to the action of the flame, or to the wearing action of the piston.

While I have herein described in some detail a particular embodiment of my invention, it will be apparent to those skilled in the art that numerous changes in the design and precise arrangement might be made without departure from the spirit of my invention and within the scope of the appended claims. 100

Having described my invention, what I claim is:—

1. In a gas engine, a structure encircling a combustion space and comprising concentric stationary walls separated by arcuate spaces, said wall structure having in opposite sides thereof intake and exhaust ports respectively, said ports made through both the inner and outer walls, two opposed arcuate valve-members, respectively controlling the inlet and outlet ports, sliding in said arcuate spaces, and means for independently operating said valves. 110

2. In a gas engine, a structure encircling a combustion space and comprising concentric stationary walls separated by arcuate spaces, open at one end said wall structure having in opposite sides thereof intake and exhaust ports respectively, said ports made through both the inner and outer walls, two opposed arcuate valve-members, respectively controlling the inlet and outlet ports, sliding in said arcuate spaces, and removable through the open end thereof, and means for independently operating said valves. 120

3. In a gas engine, a structure encircling a combustion space and comprising two stationary, spaced-apart, concentric walls having port-couples therethrough, the port-couples in opposite sides of the wall structure being respectively intake and exhaust ports, two arcuate, ported valve members slidable axially in the space between said walls, each controlling a port-couple; and means for independently sliding said valve-members.
4. In a gas engine, a structure encircling a combustion space and comprising two stationary, spaced-apart, concentric walls having port-couples therethrough, in different planes, the port-couples in opposite sides of the wall structure being respectively intake and exhaust ports, two arcuate valve members slidable axially in the space between said walls, each controlling a port-couple and having oppositely facing openings in different planes connected by an internal passage through the valve member; and means for independently sliding said valve-members.
5. In a gas engine, a structure encircling a combustion space and comprising two stationary, spaced-apart, concentric walls having port-couples therethrough, in different planes, the port-couples in opposite sides of the wall structure being respectively intake and exhaust ports, two arcuate valve members slidable axially in the space between said walls, each controlling a port-couple and having oppositely facing openings in different planes connected by an internal passage through the valve member; packing rings on the inner wall above and below the ports in said wall coacting with the inner surfaces of the valve-members.
6. In a gas engine, the combination with a cylinder, of a valve structure providing two axially extending, curved fixed walls having ports at different planes, and slide valve members working between said walls and having longitudinal passages therethrough open only at the passage-ends for connecting said ports.
7. In a gas engine, the combination with a cylinder, of a valve head comprising axially extending parallel fixed walls having ports therethrough at different planes, slide valve means axially movable between said walls and having longitudinally extending passage ways open only at the passage ends for establishing communication between said ports in the parallel walls, and means for actuating said valve structure.
8. In a gas engine, the combination with a cylinder, of a detachable valve head comprising an inner cylinder transversely closed above its lower end and having lateral ports below said closures, an outer sleeve spaced apart from said cylinder, and having lateral ports therethrough, two arcuate valve members mounted between said cylinder and sleeve, and means for independently moving said valve members, there being in the valve sections passages for effecting communication between the inlet ports and the outlet ports respectively of the cylinder and sleeve.
9. The combination with a gas engine cylinder, of a valve head comprising an inner cylinder transversely closed above its lower end and having ports below said closure, a sleeve encircling and spaced apart from said cylinder and having ports at a different plane from the ports in said cylinder, two arcuate slide-valve members between the cylinder and sleeve having longitudinally extending passages for effecting communication respectively between a port of the cylinder and the port of the sleeve, and means to actuate said slide valve members independently.
10. The combination with a gas engine cylinder, of a valve head comprising an inner cylinder transversely closed above its lower end and having ports below said closure, a sleeve encircling and spaced apart from said cylinder and having ports at a different plane from the ports in said cylinder, two arcuate slide-valve members between the cylinder and sleeve having longitudinally extending passages for effecting communication respectively between a port of the cylinder and the port of the sleeve, means to actuate said slide valve members independently, and packing rings carried by said cylinder co-acting with the inner surface of said slide valve members.
11. The combination with a gas engine cylinder having closed peripheral walls, a detachable head for said cylinder comprising a cylindrical extension having a combustion space smaller in diameter than the cylinder and axially communicating therewith and having ports through its side walls, a sleeve surrounding and spaced apart from said cylindrical extension having ports in its side wall, and two semi-cylindrical valve members sliding between said cylinder and sleeve, each having a passage for communication between one of the extension ports and one of the sleeve ports, and means for mechanically reciprocating said valve members.
12. The combination with a gas engine cylinder having closed peripheral walls, of a detachable head comprising a flanged, transversely closed cylinder, a flanged open-ended sleeve, said head, cylinder and sleeve bolted through their flanges to the gas-engine cylinder and providing between them an annular space, there being port-couples opening through said head-members, said couples oppositely placed, and the ports of each couple in different planes, two axially slideable, arcuate valves in said annular space each controlling a port-couple, and

means for independently reciprocating said valve-members.

13. In a gas engine, a structure encircling a combustion chamber, having its side walls hollowed to provide space for vertical slide valves and having an intake port-couple and an exhaust port-couple each port couple opening in both opposing walls of its space, two vertically reciprocatable valve-members having transverse passages respectively controlling said inlet and exhaust ports, and means for independently reciprocating said valve-members.

14. In a gas engine, a cylinder having closed peripheral walls, a structure, surrounding a combustion space that is closed at one end and at its other end opens to said cylinder, said structure having its side walls hollowed vertically to provide space for vertically slideable valves, and having intake and exhaust port openings leading to the combustion space, two vertically reciprocatable valve-members for the intake and exhaust ports respectively, each having a transverse passage controlling its associated ports, a shaft beyond said valves, and independent connections from said shaft to said valves for working the latter.

15. In a gas engine, a cylinder, a struc-

ture surrounding a combustion space that is closed at one end and is open at its other end to the cylinder, said structure having spaced-apart walls affording slide-space therebetween and having at different peripheral points two port couples having their openings in the spaced walls non-aligning; two vertically slideable valves controlling the respective port couples, each said valve having a passage with non-aligning orifices, and means for independently working said valves.

16. In a gas engine, a cylinder, a structure surrounding a combustion space that is open at one end to the cylinder, said structure having spaced-apart annular walls provided with intake and outlet ports at different peripheral points, two vertically reciprocable valves controlling the respective ports, said valves jointly making an annulus and contacting edge-to-edge, and means for reciprocating said valves.

In testimony whereof I hereunto set my hand in the presence of two subscribing witnesses.

GEORGE W. HAURY.

In the presence of—
WILLIAM KAISER,
ROBERT J. PINKERTON
